ATOMIZER

Filed July 26, 1927

Inventor:
Thomas J. Holmes

by
Geo. N. Goldard, atty.

UNITED STATES PATENT OFFICE

THOMAS J. HOLMES, OF EVERETT, MASSACHUSETTS, ASSIGNOR TO T. J. HOLMES COMPANY, INC., OF EVERETT, MASSACHUSETTS, A CORPORATION OF MASSACHUSETTS

ATOMIZER

Application filed July 26, 1927. Serial No. 208,475.

This invention relates to liquid atomizers, and is particularly intended to provide a convenient and efficient form of atomizer so constructed that the atomizer may be adjusted to regulate the volume of spray, when in use, and may be tightly sealed against accidental escape of the liquid from the bottle or container through either the liquid-discharge passage or the bottle-venting passage, so that the device may safely be carried in a trunk or traveling bag without danger of spilling the liquid and injuring the contents of the bag.

In my former Patent No. 1,514,084, dated Nov. 4, 1924, I described a leak-proof atomizer operating on a principle similar to that of the atomizer herein described, but in the specific forms illustrated in that invention the rotatable axially adjustable spray-controlling member formed one member of the atomizing nozzle or chamber, and hence the size and proportions of that chamber were varied by adjusting the spray-controlling and sealing member. The present construction is in the nature of an improvement on the forms shown in the patent aforesaid, inasmuch as it makes provision for a fixed spray chamber of uniform size that is not affected by the adjustment of the spray-controlling and sealing member. Not only is the atomizing chamber of fixed form and capacity in the present case, but, with the construction and arrangement used, it is unnecessary to bore the rotatable axially adjustable spray-controlling and sealing member. These and other features of the invention will be particularly described in the following specification and will be defined in the claims hereto annexed.

In the accompanying drawings I have shown slightly different forms of construction embodying the principles of this improvement, in which:

Figure 1 is an enlarged vertical or longitudinal sectional view of my improved atomizing stopper applied to a bottle-container.

Figure 2 is a detail showing a central vertical section on one side in a plane at right angles to Figure 1 to show the air-venting passage.

Figure 3 is a plan view of the stopper with

the sealing and regulating valve removed.

Figure 4 is a central vertical section showing a modified arrangement in which the valve seat plug, provided with the air and liquid passages, is arranged transversely of the stopper body, the air-supply tube being connected at the top thereof.

In Figure 1, *a* designates any suitable bottle or container usually provided with an internally threaded cap *a'* to which is secured, by an air-pipe, threaded connection with the lower end of the stopper member 1 which forms the main body of the atomizer.

In this form of the invention the stopper is provided with an interior bore extending entirely through it in which is inserted a valve-seat plug 2, provided, at one end, with a valve chamber recess 2^a, and having its other end reduced, as shown at 2^b, to form an air chamber around the liquid eduction or discharge passage 5, 5^a.

The upper valve chamber 2^a, and the lower chamber 2^b, have communication by means of an air-venting passage 3, 3^a, formed in the exterior of the plug 2, and stopping a little below the upper end of the plug where it meets a transverse port or opening 3^a leading into the valve chamber or recess.

The bottom of this valve chamber or recess forms a conical seat which is centrally perforated and which is normally closed, when the device is not in use, by the tapered conical point of the sealing valve member 7.

The stopper is transversely bored in this form to provide for the passage of a compressed air conduit 6, whose reduced tapered end 6^a, with its interior central duct, forms the inner member of an atomizing nozzle.

The outer or cap portion of the nozzle 4 is tightly secured in the transverse bore, and its hollow interior is of sufficient diameter to leave a slight clearance space around the air-delivering inner member 6^a, and is provided with an outlet aperture 4^a in line with the compressed air-passage so that, as the air is forced under pressure through the air duct, it draws minute quantities of the liquid through the liquid-discharge passages and atomizes the liquid, delivering a fine spray through the nozzle orifice 4^a.

The liquid passes up through the pipe 5, extending down below the surface of the liquid in the bottle a, through the duct or bored passage 5^a, around the compressed air-pipe 5^b, which is annularly grooved to provide such passage, and into the lower conical portion of the valve receiving chamber 2^a, adjacent to the liquid outlet passage or port 2^c that is annularly sealed by the tapered point 10 of the valve 7. The compressed air tube is of smaller diameter than the transverse bore in the plug and in the nozzle cap to allow the liquid, when the valve is retracted from its seat by reverse rotation, to be drawn through 15 the liquid-discharge passages to the nozzle by the suction produced by the passage of the compressed air through the nozzle.

The threaded valve 7, when rotated in either direction, is adjusted to, or from sealing position. In addition to the valve surface of its point or tip, it has an additional conical valve seat 7^a, adapted to tightly seal the upper end of the valve chamber 2^a at the same time that its point or tip closes the orifice 2^c, at the 25 bottom of the said valve chamber, thereby tightly sealing the valve chamber against the possible escape or seepage of liquid through the air-venting passage when the valve is closed. It will, therefore, be seen that the 30 valve chamber can be securely sealed at both ends so that when the valve is tightly set the liquid can not escape through the liquid discharge passages and through either the bottom or the top of the valve chamber, nor can 35 the liquid escape from the valve chamber in either direction after it has passed through the air-venting duct.

In Figure 4 I have shown a somewhat modified arrangement embodying the same principles of construction in which the inserted plug containing the valve-seats for the sealing device and the air and liquid passages is mounted in a transverse bore with the air supply pipe led in at the top of the stopper.

In this form of the device the head or stopper 10 is provided with a transverse bore passing entirely through the stopper horizontally. The lower end of this stopper is provided with a large vertical bore or passage 10^a whose upper end is counterbored on a smaller diameter for the snug insertion of the liquid-delivery tube 11 up which the liquid flows to suitable valve-control passages to the aspirating or atomizing nozzle.

The valve-seat plug 12 has its delivery end reduced in diameter to form the inner member 12^a of the atomizing nozzle, this reduced nozzle member being surrounded by a slightly separated nozzle cap 14, having a delivery orifice in line with the air passage 12^b in the plug which communicates, through the passage 13^a, with the air-supply pipe 13 which is tightly secured in a socket formed in the upper end of the stopper.

When the device is in use the liquid passes

through the liquid-conveying tube 11 and port 10^b into an annular passage 12^c formed in the exterior of the plug 12 before the plug is inserted. Opposite its nozzle end the plug is provided with a valve-sealing chamber 70 having communication with the liquid-tube 11 through the annular passage, and a short port or passage 12^d outside of the liquid outlet passage 12^c from which the liquid flows between the two nozzle members to the aspirating chamber adjacent to the atomizing or spraying chamber where by the action of the air is atomized and blown out through the nozzle orifice. 75

A bottle-venting passage 16 affords communication between the chamber 10^a, outside of the liquid tube 11, and the rear portion of the valve-chamber inside of the outer edge of the valve chamber.

Both the forward or outlet end and the rear end of this valve chamber are engaged, respectively, by the tapered point of the valve plug 15 and by the shoulder 15^a proportioned to engage the rear end-edge of the valve chamber to provide two tight sealing joints. 85 The valve plug is opened or closed by movement in a radial direction produced by its screw-threaded engagement with the interior threaded wall of the valve chamber, that portion of the plug between the screw threads and the sealing surface 15^a being slightly reduced in diameter to allow free passage of the air for venting purposes when the plug is slightly retracted for atomizing purposes. As the liquid can escape from the bottle stopper only through the passages 12^d and 16, leading into the valve chamber, and as the valve chamber is hermetically sealed against the passage of the liquid outward therefrom in either direction by the two annular sealing surfaces of the valve, it is obvious that when the valve plug is tightly seated by screwing it in there is no possibility of the slightest leakage of the liquid as both sealing joints are absolutely tight. In this respect the action is precisely like that described in reference to the form of the device shown in Figures 1, 2 and 3, although the details of construction are somewhat varied. 95 100 105 110 115

What I claim is:

1. A liquid atomizing stopper embracing in its construction a body member provided with liquid-discharging and bottle-venting passages, the former leading to an atomizing chamber of fixed proportions, an axially adjustable rotatable sealing member arranged by its axial adjustment to open and to close the liquid-discharge and the bottle-venting passages simultaneously without affecting the size of the atomizing chamber, the stopper being also provided with a compressed air duct leading to the centre of the atomizing chamber. 120 125

2. A liquid atomizing stopper embracing 130

in its construction a main body member adapted for attachment to a liquid container and provided with a liquid-atomizing chamber formed between outer and inner spaced walls located in fixed relation to each other, unaffected by the opening or sealing of the atomizer, the stopper being provided with a liquid-discharge passage leading to said atomizing chamber from the interior of the bottle, a separate bottle venting passage leading to the exterior of the stopper body, an axially adjustable threaded valve having annular closure surfaces arranged, when the plug is screwed inward, to close the liquid discharge and the bottle-venting passages against the escape of liquid, the stopper being provided with a compressed air duct leading to the atomizing chamber.

3. A liquid atomizer embracing a stopper body bored to receive a fixed plug, a plug secured in said bore and provided with an exterior passage for the liquid and a central passage for compressed air, a hollow fixed nozzle-cap forming an atomizing chamber in communication with the liquid passage and with the compressed air passage, an axially adjustable sealing valve formed to close the liquid discharge passage and also a bottle-venting passage formed in the stopper body when screwed to its seat.

4. In a liquid atomizer, the combination of a bottle stopper member provided with a bore passing entirely through it, a valve-seat plug provided with a conical centrally apertured valve seat, an atomizing nozzle provided with a central compressed air passage, and having communication with the interior of the bottle to which the stopper is affixed by means of liquid-discharge passages having communication through said central perforation in the valve seat, the stopper having an air-venting passage for the interior of the bottle, and a conical pointed axially movable rotatable valve arranged to tightly close the central aperture in said valve seat to prevent escape of liquid therethrough, said valve having another portion acting to simultaneously seal the air vent.

5. An atomizing stopper for a bottle or the like embracing in its construction a stopper body provided with an atomizing chamber, and with separate liquid-discharge and bottle-venting passages, said stopper having a valve-receiving recess at a distance from the atomizing chamber provided with co-axial spaced annular sealing seats, through one of which communication between the bottle and the atomizing chamber is effected by means of the liquid-discharge passage, and axially adjustable sealing means provided with spaced annular sealing surfaces arranged respectively to be engaged with the corresponding annular sealing seats.

6. An atomizing stopper for a bottle or the like embracing in its construction a stopper

body provided with an atomizing chamber, and with separate liquid-discharge and bottle-venting passages, said stopper being provided also with a valve-receiving recess having spaced annular co-axial sealing seats, one of which has a central opening forming a port in the liquid discharge passage intermediate of its ends, and a valve member located in said recess and having co-axial annular sealing surfaces spaced to engage the corresponding annular seats at the same time to prevent escape of liquid through the aforesaid passages when the valve is closed, said stopper being also provided with a compressed-air duct leading to said atomizing chamber.

7. An atomizing stopper for liquids embracing in its construction a stopper body provided with an atomizing chamber, and with separate liquid-discharge and compressed-air passages leading thereto, said liquid-discharge passage including intermediate of its ends a valve controlled port, an axially adjustable taper-ended valve movable into said port to seal it against the escape of liquid therethrough, the stopper being provided with a bottle-venting passage whose outer end is sealed by said valve when the valve is moved axially to seal the the said port.

8. An atomizing stopper provided with an atomizing chamber and with liquid-discharge and bottle-venting passages, the former passage including a centrally apertured end portion of a valve-receiving recess, formed in the stopper, into which the liquid from the bottle enters by a lateral port, and from which it flows to the atomizing chamber through said central aperture, an axially adjustable valve for sealing said central aperture, said valve being provided also with means for sealing the outer end of the bottle-venting passage against the escape of liquid.

In witness whereof, I have subscribed the above specification.

THOMAS J. HOLMES.
